SOCK SUPPORT

Ole Kjole Gjertsen, New York, N. Y.

Application October 16, 1947, Serial No. 780,124

1. Claim. (Cl. 2—303)

1

The present invention relates to sock supports and garters, and especially to such supports which derive their position and stability from attachment to the ankle of the wearer.

The main object of my invention is to provide a sock support of the character indicated which requires no suspension from the upper part of the leg of the user or from the garments from above, but has a portion attached to the ankle which suffices to maintain the support in useful position.

Another object is to provide such a sock support which has one portion surrounding the ankle of the wearer within the sock and another portion attached to the first mentioned portion, and directly holding the sock in place by suspension.

A further object is to largely conceal the supporting members supporting a sock in order to render the same as unobtrusive as possible.

A still further object is to have a sock support which is readily applied in as accessible a position as possible upon the leg of the wearer, that is, upon the ankle with a minimum diameter, which also makes the device smaller than if applied higher.

It is also an object to have the sock support made of two separable portions, the one being capable of attachment to the ankle and the other to the upper portion of the sock, the latter being attachable to the first portion above the sock but normally capable of remaining attached to said sock when detached from the first mentioned portion.

It is even an object to introduce a novel form of sock support which has a new sales appeal and is manufactured cheaply to sell for a very reasonable price.

Other objects and advantages will appear in further detail as the specification proceeds.

In order to bring out more comprehensively the features of this invention, the same is illustrated in a practical form in the accompanying drawings forming part hereof, and in which,

Figure 1 is a front elevation of the ankle and foot of a wearer covered with a sock and showing the ankle support in position, with part of the sock in section to disclose details of the sock support;

Figure 2 is a front elevation of the sock support alone;

Figure 3 is a similar view of a rear portion thereof;

Figure 4 illustrates a certain modification of the lower portion of the sock support;

Figure 5 shows a still further modification of said lower portion of said sock support;

2

Figure 6 is a transverse section taken on line 6—6 in Figure 4; and

Figure 7 is a transverse section taken on line 7—7 in Figure 5.

Throughout the views, the same reference numerals indicate the same or like parts.

Garters and suspension means for supporting socks have been used for a long time, but either they must be attached to garments worn by the user or they are attached to the leg in some way to constrict the latter in an undesirable way. It is also well known that garters are usually worn up along the leg in a somewhat inaccessible position, not to mention that they are more or less unsightly and at best give the impression of being mere makeshifts.

Now, I have found that it is not necessary to have such garters attached from above that hang down in unsightly manner while constricting the soft parts of the leg, as it is easily possible to have special support means which are convenient to apply and use which are almost completely concealed and accessible for adjustment or removal at will.

25 Hence, in the practice of my invention, and referring again to the drawing, a strap member 8 is mounted upon the ankle 9 with the end 10 of the strap engaging in a buckle 11 within a sock 12, and is provided with an upright strip 13 of rather stiff material secured to the strap member by means of a bridge or connecting piece 14, the latter being secured exteriorly upon the strap member and forming an upward limited projection on the upright strip member 13, so as to form part of the latter for all practical purposes.

30 The lower part of the upright strip in the form of the bridge member or connecting piece 14 is widened along the strap 8, 21, or 23, as the case may be and has the bottom end extended a distance below the strap in each case to form an extensive reinforcement for the strap and the upright strip 13 at the junction thereof, while also having the laterally widened portions and the upward projection joined by diagonal portions covering the meeting angles of the upright and strap member above the latter, as may readily be seen by noting Figure 2 and particularly in conjunction with Figures 4 and 5. The strap member may be made of leather, plastic or the vinyl series or any other material, while the connecting piece may also be made of such material and secured thereto by cementing, riveting or sewing the same thereto. The strap member may also be reinforced outside with a stiffening strip of semi-hard material. Upon the upper portion of

40

45

50

55

the upright strip 13 are fixed a row of snap fasteners 15 which are spaced uniform distances apart, the strip being stiff enough to resist bending out over the upper end of the sock. A sock suspension member 16 has a pair of spaced apart snap buttons 17 normally engaging with the snap fasteners 15 and provided with a conventional button 18 and loop 19 combination for securing the upper end of the sock thereto. As the snap buttons on the suspension member can be attached to the fasteners at any height it is evident that socks of various lengths may be accommodated.

Although a buckle 11 has been described as engaging with the end of the ankle strap, it may be replaced by a loop of material 20 similar to that of the strap 21 to receive end 22 of the latter as shown in Figures 4 and 6, the strap being preferably stiff and somewhat resilient so that it will tend to close about the ankle. On the other hand, as shown in Figures 5 and 7, the ankle strap 23 may have its end 24 provided with a snap button engaging with a snap fastener 25 on the strap proper, at 26.

Manifestly, variations may be resorted to and parts and features may be modified or omitted, within the scope of the appended claim.

Having now fully described my invention, I claim:

In a sock support comprising a strap member for encircling the ankle of the wearer, an upright mounted at the lower end thereof upon said strap member and upon the upper end having a sepa-

rable fastening means, the features which include a sock suspension member having means for engaging with and retaining a sock attached thereto and at least one fastening member adapted to engage with the separable fastening means as the sole connection between said upright and said sock suspension member, and a bridge or connecting piece secured exteriorly upon the strap member and the lower end of said upright having an upward projection along said upright and being widened laterally in both directions along the strap member and also having the bottom thereof extended below said strap member to form an extensive reinforcement for the strap member and upright at the junction thereof and having the lateral widened portions and the upward projection joined by diagonal portions covering the meeting angles of said upright and strap member above the latter.

OLE KJOLE GJERTSEN.
